CHARLES S. SEGROVE, OF NEW HAVEN, CONNECTICUT, ASSIGNOR TO SARGENT & COMPANY, OF NEW HAVEN, CONNECTICUT, A CORPORATION OF CONNECTICUT.

LOCK.

1,188,563.

Specification of Letters Patent. Patented June 27, 1916.

Application filed September 23, 1911. Serial No. 650,899.

To all whom it may concern:

Be it known that I, CHARLES S. SEGROVE, of the city of New Haven, county of New Haven, and State of Connecticut, have invented new and useful Improvements in Locks, of which the following is a full, clear, and exact description when taken in connection with the accompanying drawings.

10 My invention relates more particularly to locks having a latch bolt which is retractable by inside and outside manual retracting members respectively, suitable stop work or night latch mechanism being provided for dogging the outside retracting member when desired.

The primary objects of the invention are to provide improved means for dogging or deadlocking the night latch mechanism; to furnish means within the lock, operated by a key or otherwise, to throw into protracted position a releasing night latch slide accessible through the face plate; to provide means which will not only actuate the releasing night latch slide to dog the outside manual retracting means, but will also deadlock said slide in its protracted position; to provide means to actuate the night latch mechanism from either side of the door; to construct a lock so that one of the manual retracting devices for the latch bolt may be dogged and released from the face of the lock and dogged from either side of the lock; to furnish a construction in which the night latch mechanism may be moved from released to dogging position by the actuation of a dead bolt embodied in the lock; to provide a lock in which one of the night latch members associated with the latch bolt is bodily movable with the dead bolt as the latter is protracted; and to so construct and arrange the parts of the mechanism that the key which retracts the latch bolt from the outside of the door is operative from the same side of the door to actuate a dogging means associated with the manual retracting means for the latch bolt.

To these ends, and others which will appear as the description proceeds, the invention consists in the novel features and combinations of parts to be hereinafter described and claimed.

In the accompanying drawings, Figure 1 is a side view in elevation of the lock

with the cap plate removed, and with the dead bolt retracted and the latch bolt protracted, and with the night latch mechanism out of dogging position. Fig. 2 is a similar view partly broken away of the lower part of the lock with the night latch mechanism dogging the outside hub. Fig. 3 is a similar view to Figs. 1 and 2 with the night latch mechanism in dogging position, and with the deadbolt protracted. 60 Fig. 4 is a view similar to Fig. 3, but with the deadbolt partly retracted by the dog of the cylinder lock which is operated by a key from the outside. Fig. 5 is a view similar to Fig. 4, but with the deadbolt 70 partly protracted through the medium of the cylinder dog, and with the night latch dogging mechanism shown in a position where it is starting to force the slide of said night latch mechanism outwardly, and 75 with the locking slide of said mechanism shown as carried by such movement partly into engagement with the outside hub. Fig. 6 is a side view in elevation with the dead bolt retracted, and with the latch bolt retracted by means of the dog of the cylinder. Fig. 7 is a detail side view in elevation of the upper part of the lock with the tumbler of the deadbolt removed, and showing the deadbolt protracted. Fig. 8 is a view similar to Fig. 7 showing the coöperation of the cylinder dog with the latch bolt reTRACTING levers. Fig. 9 is an edge view of the divided hub. Fig. 10 is a detail of one of the latch bolt retracting levers. Fig. 11 is a detail of the other latch bolt retracting lever, and Fig. 12 is a detail of the deadbolt tumbler.

In all figures, similar letters of reference represent like parts.

Referring to the drawings, 1 is the casing of the lock. Mounted within the casing is a latch bolt 2 having a shank 3. The shank is provided at its inner end with a head 4 adapted to be engaged by a shoulder of a sliding spring pressed yoke 5, which yoke is adapted to be actuated by the wings 6 of a hub, which is divided into an outer and inner part 7 and 8, respectively, each hub being connected to and controlled by a separate knob (not shown).

Mounted in the casing and adapted to project through the face plate secured thereto are thumb stop members 9 and 10 of which the lower member is adapted to provide a

dogging or deadlocking device to engage a notch 11 formed in the outer hub portion 8 of the divided hub, so that when said slide 9 is pushed inward, the outside hub, and consequently the outside knob will be dogged against movement. The usual connecting lever 12 is provided between the slides 9 and 10, whereby upon pressing the slide 10 inwardly the slide 9 will be withdrawn from 10 dogging engagement with the hub.

The deadbolt 14 is provided with a tumbler 15 which co-operates with the tumbler stump 16 projecting from the casing, and which has a projection 17. This projection 15 is adapted to be engaged by the wings 19 of a hub 20 rotatably mounted in the casing and having a suitable actuating instrumentality, such as a thumb turn (not shown). The upper edge of the tumbler is provided 20 with a projection 21 extending between the talons 22 of the dead bolt. The projection 21 and talons 22 are adapted to be engaged by a rotatable dog 23 of a suitable cylinder lock of the usual type actuated by a key 25 from the outside.

Carried by the deadbolt 14 is a spring 39 pressed lever 24 having at its inner end a rounded shoe 25 (see Fig. 11) projecting inwardly from the lever. This shoe is adapted to bear upon the shoulder 26 (see Figs. 7, 8 and 10) of an elongated flat lever 27 lying against the rear wall of the casing and supported thereby and having its lower end projecting in front of the 35 head 4 of the latch bolt in position to retract said latch bolt when the lever is rocked rearwardly on its pivot.

The dead bolt 14 carries at its lower part 49 a projection 13 located in line with the inner end of the releasing slide 10 and movable in the same line as said slide. Thus when the bolt is protracted the projection 13 will be carried against the inner end of the releasing night latch slide, and if the latter is in 45 its retracted position, said projection will force it outwardly thereby moving the dogging slide 9 in the opposite direction and carrying it into dogging engagement with the outside hub.

53 The operation of the device is as follows: The outside knob and its hub may be dogged in the usual way by pressing in the slide 9. Assuming that the door has been shut and it is desired to lock the same against entrance and against tampering with the night latch mechanism, the hub 20 is turned by its operating instrumentality so as to protract the dead bolt 14, which movement is effected by the engagement of a wing 19 69 with the projection 17 of the tumbler, whereby the tumbler is released from the stump 16 and carries forward the dead bolt. In the protraction of the bolt the stop projection 13 which is directly behind the slide 65 10 will be carried against the inner end of

the latter, and if said slide is retracted will force the same to protracted position, or if it is protracted will abut against its inner end, in either event, serving to block the actuating slide 10 in its outer position by 70 the protraction of the bolt. To unlock the door from the outside, the cylinder dog 23 is rotated anti-clockwise as shown in Fig. 4, in which movement the dog will first enter between the upper talons 22 of the dead bolt 75 and depress the tumbler so as to release the same, and then retract the dead bolt. To retract the latch bolt, the dog 23 after its retraction of the dead bolt is given a second rotation in anti-clockwise direction, where- 80 upon it will be brought in contact with the lever 24 which has been carried beneath the dog by the retraction of the dead bolt, and the retraction of the latch bolt is effected by the engagement of the dog with said lever, 85 as shown in Fig. 6.

The deadbolt is protracted and the night latch mechanism dogged from the outside by turning the dog 23 clockwise, as shown in Fig. 5, which movement carries the stop 90 projection against the inner end of the slide 10 so as to force the latter outwardly and the stop abuts against the end of the slide to prevent the release of the outer knob. It will be seen that by the above ar- 95 arrangement the night latch mechanism when in released position will be set in position to dog the outside hub whenever the dead bolt is protracted, and will remain in dog- 100 ging position after the dead bolt has been retracted, thus insuring the operation of the night latch mechanism without the necessity of manually pressing the slide 9. It will be manifest that if the night latch mechanism is in released position it will not 105 only be moved to dogging position by the operation of the thumb-turn at one side of the door or the key at the opposite side of the door, but it will also be effectively dead-locked as long as the deadbolt is protracted. 110

Having thus described my invention, what I claim is:—

1. In a lock, the combination with a night latch slide, of a dogging member therefor manually protractible in the line of movement of said slide to engage the same, substantially as described.

2. In a lock, the combination with a night latch slide, of a dogging member slidable in line with the night latch slide and operable to abut against the inner end thereof to stop the slide, substantially as described.

3. In a lock, the combination with a night latch mechanism having an actuating slide, of a dogging member mounted behind the inner end of the slide and slidable in line with said slide to abut against and stop the same, and means operable from one side of the door for operating said dogging member, substantially as described.

4. In a lock, the combination with a dead-bolt, of night latch mechanism, and means operable by the protraction of said bolt for dogging said night latch mechanism, substantially as described. 10
5. In a lock, the combination with a bolt, of night latch mechanism, dogging means for said mechanism, and manually operable means for jointly protracting said bolt and moving said means into dogging position, substantially as described. 15
6. In a lock, the combination with a bolt, of night latch mechanism having a slide, and a dogging member carried by said bolt and manually protractible with said bolt into engagement with said slide, substantially as described. 20
7. In a lock, a latch bolt, manual retracting means therefor, night latch mechanism associated with said means, and a single mechanism operable from the outside of the door to retract said latch bolt or actuate said night latch mechanism; substantially as described. 25
8. In a lock, the combination with a latch bolt, retracting means therefor, and night latch mechanism associated with said retracting means, of a dead bolt, and means for setting the night latch mechanism in dogging position automatically upon the protraction of said dead bolt; substantially as described. 30
9. In a lock, the combination with a latch bolt, retracting means therefor, and manually operable night latch mechanism associated with said retracting means, of an auxiliary sliding member for setting said night latch mechanism in its dogging position; substantially as described. 35
10. In a lock, the combination of a latch bolt, manual retracting means therefor at the outside of the door, night latch mechanism for dogging said means, and means actuated by a key at the outside of the door to retract said latch bolt or actuate said night latch mechanism; substantially as described. 40
11. In a lock, the combination with a latch bolt, of a rotary hub for actuating said latch bolt, a dead bolt, and a dogging member for engaging the hub directly to prevent its rotation, operated by the protraction of the deadbolt, substantially as described. 50
12. In a lock, the combination with a latch bolt, of mechanism for actuating said latch bolt, independently operable means for deadlocking said latch actuating mechanism, a dead bolt; and means for actuating said deadlocking means by the protraction of the deadbolt, substantially as described. 55
13. In a lock, the combination with night latch mechanism manually operable through the face plate, of additional manual means for operating said mechanism from one side of the door, substantially as described. 60
14. In a lock, the combination with night latch mechanism, means manually operable through the face plate to set said mechanism in dogging position and release it therefrom, and additional means operable from one side of the door to set said mechanism in dogging position only, substantially as described. 70
15. In a lock, the combination with night latch mechanism, of a bolt, and means operable by the protraction of the bolt for setting said night latch mechanism in dogging position, said bolt being retractable independently of said night latch mechanism, substantially as described. 75
16. In a lock, a case, a latch bolt therein, manual retracting means for said latch bolt, night latch mechanism associated with said means and including a releasing slide accessible through the face of the case, and means in the case to actuate said releasing slide; substantially as described. 80
17. In a lock, a case, a latch bolt therein, manual retracting means for said latch bolt, including a notched hub or roll-back, a stop member in the case movable into and out of the notch of said hub, and separate means for actuating said stop member from the respective sides of the door; substantially as described. 85
18. In a lock, a case, a latch bolt therein, manual retracting means for said latch bolt, night latch mechanism associated with said means and including a releasing slide accessible through the face of the case, and key operated means in the case to protract said slide; substantially as described. 90
19. In a lock, a case, a latch bolt therein, manual retracting means for said latch bolt including inside and outside hubs, a dogging member for engaging the outside hub, and a thumb-turn member for operating said dogging member, located at the inner side of the door; substantially as described. 95
20. In a lock, a case, a latch bolt therein, manual retracting means for said latch bolt, night latch mechanism associated with said means and including a releasing slide accessible through the face of the case, and a dead bolt in the case having means to protract said slide as the dead bolt is protracted; substantially as described. 100
21. In a lock, a latch bolt, retracting means therefor, night latch mechanism associated with said retracting means, and thumb-turn mechanism to actuate said night latch mechanism; substantially as described. 110
22. In a lock, a latch bolt, retracting means therefor, night latch mechanism associated with said retracting means, and thumb-turn mechanism for moving said night latch mechanism into dogging position; substantially as described. 115
23. In a lock, a latch bolt, retracting means therefor, night latch mechanism as- 120
- 130

- 1
sociated with said retracting means and including a releasing slide accessible at the face of the lock, and thumb-turn mechanism to protract said slide; substantially as described.
24. In a lock, a latch bolt, retracting means therefor, night latch mechanism associated with said retracting means and including a slide, and thumb-turn mechanism to move said slide in one direction and deadlock the same; substantially as described. 70
25. In a lock, a latch bolt, retracting means therefor, night latch mechanism associated with said means and including a dogging slide and a releasing slide, and thumb-turn mechanism to protract the releasing slide and to deadlock it in protracted position; substantially as described. 75
26. In a lock, a latch bolt, retracting means therefor, night latch mechanism associated with said retracting means, and separately operable means at opposite sides of the door for actuating said night latch mechanism; substantially as described. 80
27. In a lock, a latch bolt, manual retracting means therefor, night latch mechanism associated with said means for dogging the same, and mechanism operable by a key from the outside of the door for retracting the latch bolt as the key is turned in one direction, and for shifting the night latch mechanism as the key is turned in the opposite direction; substantially as described. 85
28. In a lock, a latch bolt, manual retracting means therefor, night latch mechanism for dogging and releasing said means, mechanism operable by a key from the outside of the door for retracting said latch bolt as the key is turned in one direction, or for shifting said night latch mechanism as the key is turned in the other direction, and means for controlling said night latch mechanism from the inside of the door; substantially as described. 90
29. In a lock, a latch bolt, separately operable retracting devices therefor at opposite sides of the door, means in the lock case to dog one of said devices, and a member for actuating said means, operable by a key at the outside of the door and by a thumb-turn at the inside; substantially as described. 95
30. In a lock, a latch bolt, separately operable retracting devices therefor, means to dog one of said devices, a member to operate said dogging means, a thumb-turn member to operate said first member from one side of the door, and key actuated means to operate said member from the opposite side of the door; substantially as described. 100
31. In a lock, a latch bolt, a knob at the outside of the door for retracting the same, night latch mechanism for dogging said knob, a lock mechanism operable from the outside of the door, and a key for said lock mechanism which actuates the latter to shift said night latch mechanism as the key is turned in one direction, and to retract said latch bolt as the key is turned in the opposite direction; substantially as described. 105
32. In a lock, a latch bolt, inside and outside knobs for retracting the same, night latch mechanism for dogging the outside knob, a lock mechanism at the outside of the door, a key for said lock mechanism which actuates said night latch mechanism as the key is turned in one direction, and which retracts the latch bolt as the key is turned in the opposite direction, and thumb-turn means for controlling said night latch mechanism from the inside of the door; substantially as described. 110
33. In a lock, a case, a latch bolt therein, retracting means for said latch bolt, and night latch mechanism associated with said retracting means and movable into dogging position from the face of the case and from one side of the case; substantially as described. 115
34. In a lock, a case, a latch bolt therein, retracting means for said latch bolt, night latch mechanism associated with said retracting means and accessible at the face of the case, and means for actuating said night latch mechanism from either side of the door; substantially as described. 120
35. In a lock, a case, a latch bolt therein, manual retracting means for said latch bolt including inner and outer hubs, a stop member in the case to dog the outer hub directly, key mechanism to actuate said stop member from the outside of the door, and a thumb-turn member to control said stop member from the inside of the door; substantially as described. 125
36. In a lock, a case, a latch bolt therein, inner and outer hubs for retracting said latch bolt, a stop member for dogging the outer hub, key mechanism at the outside of the door to retract the latch bolt, and thumb-turn mechanism at the inside of the door to operate said stop member; substantially as described. 130
37. In a lock, a dead bolt, a latch bolt, retracting means for said latch bolt, and night latch mechanism associated with said retracting means and including a slide movable by and parallel to said dead bolt; substantially as described. 135
38. In a lock, a dead bolt, a latch bolt, retracting means for said latch bolt, and night latch mechanism associated with said retracting means and including a releasing slide projecting through the face of the lock and movable with and parallel to said dead bolt as the latter is protracted; substantially as described. 140
39. In a lock, a latch bolt, manual retracting means therefor comprising inner and outer hubs; a stop member to dog the outer

hub, and key mechanism at the outside of the door for shifting said stop member into dogging position when the key is rotated in one direction and for retracting the bolt 5 when the key is rotated in the other direction; substantially as described.

40. In a lock, a latch bolt, manual retracting means therefor, a key insertible into the lock from one side of the door, and mechanism 10 actuated by said key to retract said latch bolt as the key is rotated in one direction, and to dog said manual retracting means as the key is rotated in the opposite direction; substantially as described.

41. In a lock, a latch bolt, separate manual retracting means therefor at opposite sides of the door, a key insertible into the lock from the outside, and mechanism actuated by the key, when so inserted, to retract 15 said latch bolt or dog the outer manual retracting means, according to the direction of rotation of the key; substantially as described.

42. In a lock, a latch bolt, separate knob 25 operated retracting devices therefor at opposite sides of the door, means to dog the outside knob, key actuated means at the outside of the door for retracting the latch bolt when the key is rotated in one direction, and 30 means for operating said dogging means by the rotation of the key in the opposite direction when inserted at the same side of the door; substantially as described.

43. In a lock, the combination of a dead 35 bolt and its operating means, a latch bolt, hand operated means for operating the latch bolt, stop mechanism for locking the hand operated means against movement and arranged to be moved manually for unlock- 40 ing said means, and connecting means operated by the dead bolt and its operating means for automatically operating the stop mechanism to lock the hand operated means and thereby the latch bolt whenever the 45 dead bolt is protracted.

44. In a lock, a latch bolt, means controlled by outside and inside knobs for independently retracting said latch bolt, stop work mechanism arranged to be operated to 50 block the outside knob controlled means against latch retracting movement, a dead

bolt, means operable from the inside of the lock for projecting said dead bolt and for coincidentally operating said stop work mechanism to dog said outer knob controlled 55 means.

45. In a lock, a latch bolt, means controlled by outside and inside knobs for independently retracting said latch bolt, stop work mechanism arranged to be operated to 60 block the outside knob controlled means against latch retracting movement, a dead bolt, means operable from the inside of the lock for projecting said dead bolt and for operating said stop work mechanism to dog 65 said outer knob controlled means, said inside controlled means being operable to retract said dead bolt without releasing said outer knob controlled means.

46. In a lock, a latch bolt, means controlled by outside and inside knobs for independently retracting said latch bolt, a stop work mechanism arranged to be moved to dog latch retracting movement of said outer knob controlled means, a dead bolt, 75 means manually operable from the inside of the lock for projecting and retracting said dead bolt, with means automatically operated by the projecting of said dead bolt from the inside to move said stop work 80 mechanism to dog said outer knob controlled means against latch retracting movement.

47. In a lock, a latch bolt, means controlled by inside and outside knobs for independently retracting said latch bolt, stop work mechanism arranged to be moved into and out of position to dog said outside knob against latch retracting movement, a dead bolt, means controlled from the inside of the 90 lock for projecting and retracting said dead bolt, with means operable when said dead bolt is projected to move said stop work mechanism to a position to dog said outer knob. 95

In witness whereof, I have hereunto set my hand on the 20th day of September, 1911.

CHARLES S. SEGROVE.
